CARTON CONSTRUCTION

Werner Emmerich, Cincinnati, Ohio, assignor to
The Frank Tea and Spice Company, Cincinnati, Ohio, a corporation of Ohio

Application June 22, 1942, Serial No. 447,935

17 Claims. (Cl. 229—17)

This invention relates to an all paper carton for granular, or powdered materials, spices and the like, and more particularly to a carton including improved means formed integrally therewith for controlling access to sifting and pouring means provided in the top wall thereof.

An object of the invention is to provide an all paper carton which includes a pouring orifice through which the contents of the carton may be poured or removed by means of a measuring spoon or the like inserted into the carton through the pouring aperture, a perforated sifter tab which controls access to the pouring orifice, and a hinged flap member which controls access to the sifter tab. Another object of the invention is to provide a carton having the above enumerated characteristics, and which includes in addition thereto a spoon-leveling edge disposed along the upper edge of the pouring orifice.

A further object of the invention is to provide a carton with a pouring orifice of such shape and having such dimensions as to permit the insertion of the bowl of a measuring spoon therethrough in but one position relative to the orifice, viz with the upper rim or edge of the spoon bowl parallel to and adjacent said spoon-leveling edge of the orifice.

Still another object of the invention is to provide a carton having the hereinabove described characteristics, which may be fabricated from the same size blank heretofore used in the fabrication of cartons of similar size but not embodying the above enumerated features of the instant carton.

A further object of the invention is to provide an all paper carton of the character described, which may be quickly, easily and inexpensively fabricated from precut blanks into cartons ready to be filled using the same folding, gluing, filling and closing machines heretofore used to fold, glue, fill and close other cartons of similar size but not embodying the improvements of the present device.

These and other objects are attained by the means disclosed herein and described in the accompanying drawing, in which:

Fig. 1 is a plan view of a blank from which the carton of the present invention may be fabricated.

Fig. 2 is a plan view of the top, or discharge end of a completed carton fabricated from the blank of Fig. 1.

Fig. 3 is a view similar to that of Fig. 2 but showing the outer flap in an open or raised position to uncover the sifter tab, and further show-

ing the pouring orifice disposed beneath the sifter tab in dotted outline.

Fig. 4 is a perspective view of the carton of Fig. 3.

Fig. 5 is a perspective view of the carton of Fig. 4 with the sifter tab in an open or raised position.

Fig. 6 is a perspective view of the carton of Fig. 5 disposed on its side in position for use as a spoon-leveling device.

Fig. 7 is a vertical cross-sectional view of the carton taken on line 7—7 of Fig. 2.

The carton of the present invention is adapted to be delivered to the ultimate consumer in a fully assembled, rectangular condition, with ground spices or other granular or pulverant material sealed therein. In order to use the carton as a dispensing unit, an outer flap 10 may be lifted upwardly to the position disclosed in Figs. 3 and 4 for uncovering a sifter tab 11, which includes a row of perforations 12 through which the contents of the carton may be sifted. In the event that it should become desirable to pour the contents from the carton, or to remove the contents from the carton by means of a spoon, the outer edge 13 of the sifter tab may be lifted for providing a hinge or crease line along the row of perforations 12, for disposing the sifter tab in the open or raised position disclosed in Figs. 5 and 6 for uncovering pouring orifice 14. As hereinafter more fully explained, the shape of this orifice is so proportioned and designed as to permit the insertion of the bowl portion 15 of a measuring spoon in only one position, viz, with the top edge 16 of the bowl parallel to and adjacent a leveling edge 17 formed by the perforated hinge of the raised sifter tab.

After use, sifter tab 11 and the outer flap 10 may be folded back into the plane of their respective panels, being held in a closed position against accidental or unintentional opening by reason of frictional engagement between the edges of the tab and flap with the adjacent edges of their respective panels.

The completed carton comprises, broadly speaking, a substantially rectangularly shaped housing defined by a pair of side walls 18 and 19, a pair of end walls 20 and 21, a top 22 and a bottom 23. As disclosed in Fig. 1, suitable fold or score lines 24, 25, 26 and 27 set off the top-forming inner panels 28 and 29, intermediate panel 30 and outer panel 31, respectively, from the top edges of the side and end walls, whereas fold line 32 sets off the bottom-forming panels 33 from the bottom edges of said walls. A pasting flap 34

may be formed integrally with and extend laterally from side wall 18, as shown. The reference numerals 35, 36, 37, 38, 39 and 40 denote through cuts.

With reference now to the inner panels 28 and 29, it will be observed that they are provided with corresponding cut-out portions 41 and 42 defined by edges 43, 44 and 45 which are adapted, when the panels 28 and 29 are folded into a common plane, Fig. 3, to provide a substantially trapezoidal shaped pouring orifice 14. Edges 43 define the top or upper edge of the orifice, the maximum width of which is defined by edges 44, whereas the tapered side edges 45 diverge toward and terminate at the top edge of side wall 19 at fold line 27 for establishing a minimum width at the base of the orifice, between the adjacent tips 47 of the tapered wings 48. In this manner the shape of the pouring orifice is so proportioned as to admit the bowl 15 of a measuring spoon 60 only when the upper edge 16 of the spool bowl is substantially parallel with, and adjacent the upper edges 43 of the orifice. It should be understood that the dimensions of the pouring orifice may be such as to admit the bowl portion of any one of various measuring spoons, as desired.

The intermediate panel 30 may be provided with a pair of spaced cuts 49 disposed at substantial right angles to and extending inwardly from the outer free edge 13 of the panel. Cuts 49 are preferably, though not necessarily, spaced apart by a dimension equal to the lateral distance between edges 44 of the pouring orifice 14 of Fig. 3, and are of a length not exceeding, and preferably less than the distance between the top or upper edge 43 and base of said orifice. A row of perforations 12 may be arranged between the inner ends of cuts 49, the centers of said perforations being located on line X-X which is disposed in spaced parallelism with outer edge 13. The uncut portions 50 remaining between adjacent perforations 12 and between the inner ends of cuts 49 and the outermost perforations maintain the sifter tab 11 in the plane of the intermediate panel 30 until the outer end 13 of the tab is lifted, whereupon the uncut portions 50 function as hinge members about which the tab may be moved to open and closed positions.

The outer panel 31 may be provided with a pair of spaced through cuts 51 disposed at substantial right angles to, and which extend inwardly from fold line 27 by a dimension equal to, or preferably greater than the length of cuts 49 of the intermediate panel. The lateral distance between cuts 51 is preferably greater than the lateral distance between cuts 49 of the intermediate panel whereby to provide an outer flap 10 which will overlappingly cover the sifter tab. The outer edge of this flap may be defined by a plurality of through cuts 52 which are separated by uncut portions 53 which initially maintain the flap in the plane of the outer panel until the uncut portions are torn incident to a deliberate act of opening the flap. If desired a recess 54 may be provided in the outer panel for accommodating the fingernail of a person about to lift the free edge 51 of the flap.

In fabricating a carton from the blank of Fig. 1 the side, end and bottom walls may be folded and glued to provide an open topped rectangular housing which may be filled with ground spices, or any other type of granular or pulverant material.

The carton may then be closed by first folding the inner panels 28 and 29 inwardly about fold lines 24 and 25 into a common plane disposed at substantial right angles relative to the side and end walls, whereby the notched or cut-out sections 41 and 42 cooperate to form the pouring orifice 14 of Fig. 3. The intermediate panel 30 may then be folded inwardly about fold line 26 over inner panels 28 and 29 for locating sifter tab 11 over and in alignment with the pouring orifice 14, and with the row of perforations 12 registering with said orifice between edges 44. The outer panel 31 may then be folded inwardly about fold line 27 over the intermediate panel 30, whereby the outer flap 10 will overlie and lift or opened until it becomes desirable to inner panels and outer panel, exclusive of the elements 10 and 11, are secured to opposite faces of the intermediate panel in any suitable manner, such as by means of an adhesive material, to provide a tight and rigid closure for the carton.

In some instances, the packer will prefer to fill the carton in an inverted condition, in which event the top will be closed in advance of the filling operation, and the package finally closed from the bottom.

As disclosed in Fig. 6 the shape of orifice 14 is not only proportioned to admit the bowl of a measuring spoon in but one position, but it is likewise particularly adapted to provide a V-shaped pouring orifice through which the contents of the carton may be caused to flow in a well defined, easily controlled stream. Edges 44 of the inner panels and edges 49 of the intermediate panel cooperate to define reinforced side edges of the orifice which are contacted by the upper edge 16 of a measuring spoon bowl.

It should be observed that access to sifter tab 11 is controlled by the outer flap 10, and that the contents of the carton may be sifted through the perforations 12. The sifter tab need not be lifted or opened until it becomes desirable to pour or spoon the contents from the carton.

If desired, a fold line for the sifter tab 11 may be provided along axis X-X, and the row of perforations may be shifted forwardly toward the free edge 13, in order to provide a continuous leveling edge in lieu of the serrated edge 17. However, an edge such as 17 has been found, by experiment and test, to effectively and satisfactorily level off the contents of measuring spoons inserted into the orifice 14 and withdrawn with the upper bowl edge 16 in contact with the leveling edge 17.

The novel sifting-pouring-spooning dispenser top herein disclosed does not require the use of a blank any larger than has heretofore been used in the fabrication of other cartons of the same size and capacity. In addition thereto, the same machines heretofore used to assemble, fill, and seal similar cartons not incorporating my improved dispensing features, may be used to assemble, fill and seal my present carton, wherefore my improvements have not increased the cost of the finished carton.

Various changes and modifications in the structural details of the device may be made within the scope of the appended claims, without departing from the spirit of the invention. For example, the cuts 49 of Fig. 4 might converge toward the center of flap 10, thereby to define the shape of the pouring orifice 14 for precluding improper insertion of a spoon bowl. It will be observed that in the preferred embodiment, as illustrated in the drawing, the tapered wings

48, (Fig. 6), provide a pair of supports or abutments against which the sifter tab 11 abuts when in a closed position. Said wings are adapted to preclude accidental displacement of the tab into the carton incident to closing thereof.

The pouring orifice, being located in the carton top in such manner as to have its base coincidental with the carton wall 19 and flap 10, (Fig. 6), facilitates the removal of all material from the carton either by pouring or spooning, thereby avoiding waste of material that might otherwise remain as an inaccessible residue after most of the material has been dispensed. As the outer flap 10 and the sifting tab 11 do not have a common hinge line, their disposition to opened and closed positions is rendered simple and easy, while at the same time the free edge of the sifting tab 11, (Fig. 4), is located close to the hinge of flap 10, where the maximum leverage is available for holding the tab 11 closed when closing the outer flap 10. As will be evident from the disclosure of Fig. 4, all free edges of the outer flap 10 when closed, are afforded marginal support by the immoveable areas of the panel 30, so that the flap 10 may not be unintentionally displaced to the inside of the carton.

Various other advantages of merit will be recognized in the improved carton of this invention, by persons skilled in the art to which the invention appertains.

What is claimed is:

1. In a carton including a pair of spaced parallel side and end walls, the combination of a pair of inner panels extending from the end walls of the carton and folded inwardly at the end of the carton, said panels being cut away to provide a pouring opening, an intermediate panel extending from a side wall of the carton and folded inwardly to overlie said inner panels, said intermediate panel including a perforated tab hinged upon said intermediate panel and normally overlying said opening, an outer panel extending from the other side wall of the carton and folded inwardly over the intermediate panel, said outer panel including a movable flap normally overlying said tab, and means for securing said inner and outer panels to the intermediate panel.

2. In a rectangular carton including a pair of spaced parallel side and end walls and a bottom, the combination of a pair of inner panels extending from the end walls of the carton, each of said panels having a cutout portion cooperating to form a pouring orifice when said panels are folded into a common plane, an intermediate panel extending from the top edge of one side wall of the carton and folded inwardly to overlie both of said inner panels, said intermediate panel including a tab section normally overlying said orifice and including a row of perforations registering with said orifice, said tab being movable about said row of perforations as a hinge for controlling access to said orifice, an outer panel extending from the top edge of the other side wall of the carton and folded inwardly over the intermediate panel, said outer panel including a movable flap normally overlying and controlling access to said tab.

3. In a rectangular carton including a pair of spaced, parallel side and end walls, and a bottom, the combination of a pair of inner panels extending from the upper edge of said end walls, each of said panels including a cutout portion cooperating to form a substantially trapezoidal shaped pouring orifice when said panels are fold-

ed into a common plane, the base of said orifice being parallel to but of a lesser length than the upper edge thereof, said base contacting the top edge of one of said side walls, an intermediate panel extending from the top edge of the other of said side walls and folded inwardly to overlie said inner panels, said intermediate panel including a tab section normally overlying said orifice and including a row of sifting perforations registering with said orifice adjacent its upper edge, said tab adapted to be swung upwardly from the plane of the intermediate panel about said row of perforations as an axis for uncovering said pouring orifice, an outer panel extending from the top edge of said first mentioned side wall and folded inwardly over the intermediate panel, said outer panel including a movable flap normally overlying and controlling access to said tab, said flap adapted for movement about the fold line between said outer panel and that side wall from which it extends.

4. In a rectangular carton including a pair of spaced side and end walls and a bottom, the combination of a pair of inner panels extending from the upper edge of said end walls, said panels including complementary cutout portions which cooperate to form a pouring orifice in a side edge of said panels, said orifice including an upper edge spaced from and parallel with the top of one of said side walls, and a pair of depending side edges, each of said side edges extending toward the top of said side wall and at substantial right angles to the upper edge of said orifice for establishing a pair of parallel upper edges, said side edges then diverging toward and extending to the side edge of said panels for establishing a minimum width at the base of the orifice adjacent the upper edge of said side wall, an intermediate panel extending from the top of the other side wall and folded inwardly to overlie said inner panels, said intermediate panel including a tab section along its outer side edge, said tab section normally overlying said orifice, said tab section being defined by a pair of through cuts extending into said panel from its free outer edge and a row of sifting perforations extending parallel to said outer edge and between the inner ends of said cuts, said perforations registering with said orifice adjacent its upper end and between the parallel portions of its side edges, said tab adapted to be swung upwardly out of the plane of its panel to an open position about said row of perforations as an axis for uncovering said pouring orifice, the row of perforations forming a leveling edge when said tab is in an open position, the side edges of said orifice adapted to admit the bowl portion of a measuring spoon only when said bowl is inserted with the top open edge of the bowl parallel with and adjacent to said leveling edge, an outer panel extending from the top edge of said first mentioned side wall and folded inwardly over the intermediate panel, said outer panel including a movable flap normally overlying and controlling access to said tab, said flap being hinged to said outer panel on the fold between said outer panel and its associated side wall.

5. As a new article of manufacture an all paper carton fabricated from a single piece of sheet material, said carton including top, bottom and side walls, said top including an outer flap, a sifter tab and a pouring orifice, said sifter tab hingedly mounted to control access to said pouring orifice, and said outer flap hingedly mounted to control access to said sifter tab.

6. In a carton including a pair of side and end walls, and a bottom, the combination of a pair of inner panels extending from the end walls of the carton and folded inwardly into a common plane, adjacent portions of said panels being cut away to provide a pouring orifice along the upper edge of one of said side walls, an intermediate panel extending from the other of said side walls and folded inwardly to overlie said inner panels, a perforated sifter tab provided in said intermediate panel adapted to overlie said orifice, said tab adapted to be disposed in one of two normal positions relative to said orifice, open and closed, and an outer panel extending from the first mentioned side wall of the carton and folded inwardly over the intermediate panel, a flap provided in said outer panel adapted to overlie said sifter tab for controlling access to said tab.

7. A blank for a carton comprising a pair of side and end walls, a top and a bottom, each of said side and end walls including a top panel defined by a fold line, each of said top panels being separated by a through cut for providing four separate top sections hingedly secured to the upper edges of said front and side walls, those top sections secured to the end walls being formed with corresponding cut-outs which when these sections are folded into a common plane form a pouring orifice in one side edge of the resultant two piece inner top panel, the top section carried by that side wall opposite to the pouring orifice being formed with a pair of spaced through cuts disposed at substantial right angles to and extending inwardly from the free outer side edge of said top section, and a row of perforations spaced from said free outer edge and extending between and at substantial right angles to said through cuts for defining a perforated tab to overlie and control access to said pouring orifice, said flap adapted to be hinged about said row of perforations for uncovering said orifice, that top section carried by the other side wall being formed with a hinged flap adapted to cover said tab and close the perforations thereof.

8. A blank of the character set forth in claim 7, wherein the cut-outs provided in those top sections carried by the end walls are shaped whereby the pouring orifice tapers inwardly toward the side edge of the inner panel.

9. As a new article of manufacture an all paper carton fabricated from a single piece of sheet material, said carton including top, bottom and side walls, said top including an outer flap, a sifter tab and a pouring orifice, said sifter tab hingedly mounted to control access to said pouring orifice, and said outer flap hingedly mounted to control access to said sifter tab, the hinges aforesaid being remote from one another in spaced parallel relationship, to dispose a free edge of the sifter tab along the hinge of the outer flap when the flap and the tab are in closing relationship to the pouring orifice.

10. As a new article of manufacture an all paper carton fabricated from a single piece of sheet material, said carton including top, bottom and side walls, said top including an outer flap, a sifter tab and a pouring orifice, said sifter tab hingedly mounted to control access to said pouring orifice, and said outer flap hingedly mounted to control access to said sifter tab, the hinges aforesaid being remote from one another in spaced parallel relationship, to dispose a free edge of the sifter tab along the hinge of the outer flap when the flap and the tab are in closing relationship to the pouring orifice, and means

bounding the edges of the sifter tab to limit the closing movement of the outer flap toward the pouring orifice.

11. In a carton including a pair of side and end walls, and a bottom, the combination of a pair of inner panels extending from the end walls of the carton and folded inwardly into a common plane, adjacent portions of said panels being cut away to provide a pouring orifice having as one of its edges the upper edge of one side wall, an intermediate panel extending from the other side wall and folded inwardly to overlie said inner panels, a perforated movable sifter tab provided in said intermediate panel and adapted to overlie said orifice, said tab having a hinge and a free forward edge opposed to the hinge, said free forward edge being normally disposed along the upper edge of said one side wall, means on the cut away inner panels providing stops for limiting hinging movement of said sifter tab through the orifice and into the carton interior, and an outer panel hinged to the upper edge of said one side wall of the carton, and folded over onto the intermediate panel, an outer flap formed from the material of the outer panel and having a hinge connection with said one side wall edge, to overlie the sifter tab and close the perforations thereof.

12. In a carton including a pair of side and end walls, and a bottom, the combination of a pair of inner panels extending from the end walls of the carton and folded inwardly into a common plane, adjacent portions of said panels being cut away to provide a pouring orifice having as one of its edges the upper edge of one side wall, an intermediate panel extending from the other side wall and folded inwardly to overlie said inner panels, a perforated movable sifter tab provided in said intermediate panel and adapted to overlie said orifice, said tab having a hinge and a free forward edge opposed to the hinge, said free forward edge being normally disposed along the upper edge of said one side wall, and an outer panel hinged to the upper edge of said one side wall of the carton, and folded over onto the intermediate panel, an outer flap formed from the material of the outer panel and having a hinge connection with said one side wall edge, to overlie the sifter tab and close the perforations thereof.

13. In a carton including a pair of side and end walls, and a bottom, the combination of a pair of inner panels extending from the end walls of the carton and folded inwardly into a common plane, adjacent portions of said panels being cut away to provide a pouring orifice having as one of its edges the upper edge of one side wall, an intermediate panel extending from the other side wall and folded inwardly to overlie said inner panels, a perforated movable sifter tab provided in said intermediate panel and adapted to overlie said orifice, said tab having a hinge and a free forward edge opposed to the hinge, said free forward edge being normally disposed along the upper edge of said one side wall, and an outer panel hinged to the upper edge of said one side wall of the carton, and folded over onto the intermediate panel, an outer flap formed from the material of the outer panel and having a hinge connection with said one side wall edge, to overlie the sifter tab and close the perforations thereof, the outer flap being of greater size than the sifter tab whereby to overlie and receive support from portions of the intermediate panel that bound said tab.

14. In a carton including a pair of side and end walls, and a bottom, the combination of a pair of inner panels extending from the end walls of the carton and folded inwardly into a common plane, adjacent portions of said panels being cut away to provide a pouring orifice having as one of its edges the upper edge of one side wall, an intermediate panel extending from the other side wall and folded inwardly to overlie said inner panels, a perforated movable sifter tab provided in said intermediate panel and adapted to overlie said orifice, said tab having a hinge and a free forward edge opposed to the hinge, said free forward edge being normally disposed along the upper edge of said one side wall, and an outer panel hinged to the upper edge of said one side wall of the carton, and folded over onto the intermediate panel, an outer flap formed from the material of the outer panel and having a hinge connection with said one side wall edge, to overlie the sifter tab and close the perforations thereof, the outer flap being of greater size than the sifter tab whereby to overlie and receive support from portions of the intermediate panel that bound said tab, and wings on each of the inner panels aforesaid, shaped to establish a configuration of the pouring orifice approximating the cross-sectional configuration of a measuring spoon.

15. In a carton including a pair of side and end walls, and a bottom, the combination of a pair of inner panels extending from the end walls of the carton and folded inwardly into a common plane, adjacent portions of said panels being cut away to provide a pouring orifice having as one of its edges the upper edge of one side wall, an intermediate panel extending from the other side wall and folded inwardly to overlie said inner panels, a perforated movable sifter tab provided in said intermediate panel and adapted to overlie said orifice, said tab having a hinge and a free forward edge opposed to the hinge, said free forward edge being normally disposed along the upper edge of said one side wall, and an outer panel hinged to the upper edge of said one side wall of the carton, and folded over onto the intermediate panel, an outer flap formed from the material of

the outer panel and having a hinge connection with said one side wall edge, to overlie the sifter tab and close the perforations thereof, the outer flap being of greater size than the sifter tab whereby to overlie and receive support from portions of the intermediate panel that bound said tab, and wings on each of the inner panels aforesaid, shaped to establish a configuration of the pouring orifice approximating the cross-sectional configuration of a measuring spoon and means on said wings providing stops for limiting hinging movement of the sifter tab toward the interior of the carton.

16. A blank for a carton comprising a pair of side and end walls, a top and a bottom, each of said side and end walls including a top panel defined by a fold line, each of said top panels being separated by a through cut for providing four separate top sections hingedly secured to the upper edges of said front and side walls, those top sections secured to the end walls being formed with corresponding cut-outs which when these sections are folded into a common plane form a pouring orifice along one side edge of the carton top, the top section carried by that side wall opposite to the pouring orifice being formed with a pair of spaced through cuts disposed at substantial right angles to and extending inwardly from the free outer side edge of said top section, and a series of perforations spaced from said free outer edge and extending between and at substantial right angles to said through cuts for defining a perforated tab to overlie and control access to said pouring orifice, said flap adapted to be hinged along a line intersecting the through cuts of the top section that carries said cuts, for uncovering said orifice, that top section carried by the other side wall being formed with a hinged flap adapted to cover said tab and close the perforations thereof.

17. A blank of the character set forth in claim 16, wherein the cut-outs provided in those top sections carried by the end walls are shaped whereby the pouring orifice tapers inwardly toward the middle of the hinge edge of said hinged flap.

WERNER EMMERICH.

CERTIFICATE OF CORRECTION.

Patent No. 2,326,527.

August 10, 1943.

WERNER EMMERICH.

It is hereby certified that error appears in the printed specification of the above numbered patent requiring correction as follows: Page 3, second column, line 44, claim 4, for "table" read --tab--; page 4, second column, line 50, claim 12, for "lose" read --close--; and that the said Letters Patent should be read with this correction therein that the same may conform to the record of the case in the Patent Office.

Signed and sealed this 5th day of October, A. D. 1943.

Henry Van Arsdale,
(Seal) Acting Commissioner of Patents.
